UNITED STATES PATENT OFFICE

2,433,586

COMBINED FLUID PRESSURE MOTOR
AND PUMP

Harry Webberking, Scranton, Pa.

Application November 24, 1944, Serial No. 565,039

1. Claim. (Cl. 230—116)

1

This invention relates to a device for removing dust, and more particularly to such a device adapted for use in excavating, mining and similar work.

The primary object of this invention is the provision of an improved dust removing device acting on the principle of a suction fan and particularly adapted to be utilized in removing dust such as is raised by drilling with a jack hammer or the like in mines, quarries, and similar places.

An additional important object of this invention is the provision of such a device which, by virtue of its dust removal will improve and enhance the health of the operator of the jack hammer or similar power drills.

As conducive to a clearer understanding of this invention, it may here be pointed out that in such work as rock drilling, coal mining, and the like, particularly in confined spaces, such as mines or other underground installations, the dust occasioned by rock drilling or coal drilling, or the like, frequently occasions, through inhalation into the lungs of the workers a very serious disease known as silicosis. It has been determined that this disease is occasioned solely by the action of the dust particles on the lungs of the worker, and accordingly in the absence of such dust particles, or in the reduction of the quantity thereof, the incidence of the disease would materially decline. A very important object of this invention, therefore, is the provision of a device adapted to be utilized in mines or the like whereby the dust occasioned by such drilling operation is removed at the source and conveyed to a convenient receptacle, thus preventing its permeating the air, and reducing the incidence of silicosis among the workers.

Another important object of this invention is the provision of such a device which may be readily powered by means of the power normally utilized in driving the drill or jack hammer, or the like.

Other objects reside in the combinations of elements, arrangements of parts, and features of construction, all as will be more fully described hereinafter and disclosed in the accompanying drawings wherein there is shown a preferred embodiment of this inventive concept.

In the drawings:

Figure 1 is a top plan view of one form of device embodying the instant inventive concept.

Figure 2 is a side elevational view of the device shown in Figure 1 as viewed from the top, the outer cover plate being removed.

Figure 3 is a view similar to Figure 2 but dis-

2

closing the device as viewed from the opposite side, the cover plate being removed, and

Figure 4 is a sectional view taken substantially on the line 4—4 of Figure 1.

Like reference numerals refer to like parts throughout the several views of the drawings.

Having reference now to the drawings, there is generally indicated at 10 a cylindrical casing, open at its extremities and provided with flanges 11 and 12, the openings being closed by cover plates 13 and 14 secured to their respective flanges as by bolts and nuts 15 and 16 passed through suitable registering apertures in the flanges and plates. Sealing gaskets 17 and 18 are interposed between flange 11 and plate 13, and flange 12 and plate 14, respectively.

Centrally disposed in cylindrical body 10 is a central partition 19 dividing the body into two equal chambers, and provided with a centrally positioned bore, within which is positioned a sleeve 20 journaled in roller bearings 21. Suitable sealing rings 22 of felt or the like are positioned exteriorly of the bearings 21 and caps 23 serve to hold the bearings in position in their recesses in partition 19.

Positioned in sleeve 20 for rotation therewith is a shaft or axle 25 threaded at its extremities as at 26 and 27, respectively, and having mounted on the extremities thereof rotors 28 and 29. Rotors 28 and 29 are secured in position, as by sleeves 30 and 31, respectively, held in position by nuts 32 and 33 engaging respectively the threaded extremities 26 and 27.

As best shown in Figures 2 and 3, each of rotors 28 and 29 is provided with a plurality of blades 34 and 35, respectively, each having an arcuate section adjacent the hub and terminating in a relatively straight blade portion. The rotors are oppositely arranged, in such manner that their respective arcuate portions are reversed with respect to each other, for a purpose to be more fully pointed out hereinafter.

From the foregoing it will now be seen that the rotors are mounted on a common axle, and secured in relatively tight related assembly by the nuts 32 and 33, in such manner that rotation of one from a source of power is transmitted to the other, in such manner that the rotors rotate at equal speed.

The chamber containing the rotor 28 between partition 19 and cover plate 14 is provided with a peripheral inlet 40 and a centrally disposed outlet 42, while the chamber containing rotor 29 is similarly provided with a peripheral inlet 41 and outlet 43, in the center of cover plate 13.

In the operation of the device, the inlet 41 is connected through a suitable conduit to a source of compressed air, such as might normally be utilized to drive a jack hammer or the like (not shown). The inlet 40 is provided with a suitable flexible conduit (not shown) which extends to a position adjacent the hole being drilled, the outlet 42 similarly being connected to a dust receiving receptacle, such as a bag, a sack or the like (not shown). The outlet 43 serves merely as an escape for the compressed air admitted through inlet 41, and is open to the atmosphere.

From the foregoing it will be seen that as compressed air enters the inlet 41 it drives the rotor 29 in the direction indicated by the arrows in Figure 2, and exhausts to the atmosphere through the port or outlet 43. This operation through the shaft 20 drives rotor 28 in the direction indicated by the arrows in Figure 3. Due to the configuration of the blades 34, air, and correspondingly dust from the point adjacent the hole being drilled, is sucked in through the inlet 40, and discharged through outlet duct 42 into the receptacle previously mentioned.

Thus, it will be seen that the device of the instant invention serves effectively to draw the dust from its source adjacent the hole being drilled to confine the same in a suitable receptacle, and preclude its escape into the atmosphere where it might be breathed into the lungs of the worker.

Now, from the foregoing, it will also be seen that there is herein provided a device which is sturdy and durable in construction, reliable and efficient in operation, and relatively inexpensive and simple to construct and manufacture, which is powered by a normally adjacent source of power, and which accomplishes all of the objects of this invention including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

A combined fluid pressure motor and pump comprising, a cylindrical casing having detachable end covers, a diametrical partition dividing said casing into axially aligned, cylindrical, motor and pump chambers, fluid inlet means disposed peripherally in each chamber, fluid outlet means disposed axially in each cover, axially aligned, spaced anti-friction bearing means disposed in the partition in each chamber, sealing and retaining means enclosing each bearing means, a rotatable sleeve disposed centrally of said partition and of said bearing means, a shaft extending through and secured to said sleeve, a rotor in each chamber secured to an end of said shaft and means for supplying a motive fluid to one of said chambers to the rotor therein, for driving the other rotor as a pump.
